BILL BANK

Original Filed Jan. 25, 1928

UNITED STATES PATENT OFFICE

MARGARET GOEPEL, OF NEW YORK, N. Y.

BILL BANK

Original application filed January 25, 1928, Serial No. 249,436, now Patent No. 1,760,901, dated June 3, 1930.
 Divided and this application filed October 17, 1929. Serial No. 400,292.

The present invention relates to improvements in bill banks and is a division of my co-pending similarly entitled application, Serial No. 249,436, filed January 25th, 1928, 5 which has matured into patent No. 1,760,901 dated June 3, 1930.

An object of the invention is to provide a savings bank for holding bills, in which the bank may be kept locked until such time as 10 the bills accumulate in a predetermined amount; whereupon the bank may automatically open, or the internal mechanism will arrive at such condition that the bank may be manually opened.

15 More particularly, the invention has for its object to provide means whereby the rather flexible and unstiff paper bills or bank notes may be efficiently manipulated by mechanical means to enable thereby a bill bank to be provided which will induce thrift. For this purpose, a container is provided having an opening for the insertion of the bills or notes, which bills, when inserted, rest temporarily upon yieldable rests, until the cover is 20 closed, which acts to permit a follower to press down the bills past the rests, and thereby bring the bills into a position where they cannot be extracted from the container, the cover closing at the same time the entrance 25 opening of the container. To enable the operation of the collection of bills in the container to be orderly, means are provided for temporarily holding the bills in position most desirable to carry out the just-described operation.

30 Also a counter finger may be operated by the pressed down bill. The yieldable steps support the edge of the bill, as also to some extent the finger of the counter. Means hold the other edge so that the first-named 35 edge is properly supported on the steps and finger. The follower presses down, and, by the bill being between the follower and the steps and finger, a relative stiffness and rigidity is given to the bill edge.

40 Other objects of the invention are to provide a comparatively small, compact and simple form of savings bank for use in the home in which bills of one dollar or other denomination, may be treasured up and carried, 45 when full, to a banking house or institution

which if desired may issue the small bank boxes; there to be opened and the contents placed to the account of the holder of the bank box; to provide an internal construction of bank box in which the bills will be neatly and tightly held in a compact stack and obliged, in the act of stacking to operate a register for the purpose of totaling and showing the number of bills placed in the bank.

45 A further object of the invention is to provide an improved register or counter mechanism whereby the act of introducing a bill to the bank will operate the counter or register thus making known, and preserving a record 55 of, the amount of bills on deposit in the savings bank.

With the foregoing and other objects in view, the invention will be more fully described hereinafter, and will be more particularly pointed out in the claims appended thereto.

60 In the drawing, wherein like symbols refer to like or corresponding parts throughout the several views.

65 Figure 1 is a perspective view of an improved bill bank constructed in accordance with the present invention.

70 Figure 2 is a transverse vertical section taken on the line 2—2 in Figure 1.

75 Figure 3 is a longitudinal section taken on the line 3—3 in Figure 2.

80 Figure 4 is a top plan view with parts broken away.

85 Figure 5 is a vertical section taken on the line 5—5 in Figure 2.

90 Figure 6 shows in perspective a bill in folded condition ready to be placed in the bank, and

95 Figure 7 is a fragmentary section showing a slight modification.

Referring more particularly to the drawing, a box or container is provided in which 7 designates the front wall, 8 the side walls and 9 the rear wall.

100 The bottom 10 is hinged, as indicated at 11 in Figure 2, to the lower edge of the rear wall 9. A supplemental or false bottom 12 is hinged, as indicated at 13 to the main bottom 12 near its free edge. The false bottom 12

is designed to be held yieldably by a leaf or other form of spring 14 in an inclined or diagonal position within the container body.

In Figure 2 is indicated a stack of bills 15 as received directly upon the inclined false bottom 12. The extreme free edge of the main bottom 10 is provided with the upwardly and inwardly turned hook 16 to co-operate with the latch ring 17, shown more particularly in Figure 5. This latch ring is provided with a gap 18 to permit of the escape of the latch 16; and the ring is suitably supported as by an arm 19 formed in one piece therewith and bent radially of the ring and to and about the inwardly projected end of the register shaft 20, which has a bearing in the front wall 7 of the box.

The latch ring 17 is thus adapted to turn with the register wheel 21, which is secured to the shaft 20 forwardly of the front wall 7.

The wheel 21 may be provided with a series of numbers, say from 1 to 51 exposed through an opening 22 made in the supplemental front wall 23 which houses and encloses the registering mechanism. A step by step movement is imparted to the register wheel 21 by the action of the pawl or dog 24 engaging the inclined ratchet teeth 25 on the periphery of the registry wheel 21. The pawl extends downwardly from an actuating lever 26 pivoted, as indicated at 27 to either or both walls 7 and 23 and situated between such walls. The lever is normally held elevated by the action of a yieldable spring 28 which may be secured also to either front wall and bears beneath the lower edge of the lever 26. A slot 29 in the front wall 7 permits of the passage, and free vertical play of the lug or inturned end 30 of the lever 26, this end preferably having a beveled nose 31 for the easy passage of the bills 15 there-over.

On the interior of the front container wall 45 are provided one or more keepers or shelves 32 of muslin, paper thin, resilient metal or other flexible material forming temporary rests for the bills and having securing portions affixed to the front wall and operative portions extending downwardly and inwardly for the purpose of producing stops to arrest the bills in their upward movement after they have once passed below the stops.

In its upper portion the front wall 7 is 55 provided with the horizontally elongated slot 33 of a length to receive the folded bill. It will be noted that the supplemental front wall 23 terminates below the slot 33, so as not to interfere with the introduction of the bill. The slot 33 is normally secreted by the front flange 34 of the flanged cover 35. This cover is hinged or pivoted to the container or to the rear wall 9 thereof as for instance shown at 63. The top of the container is closed by a permanent top 37. Within the container is a

follower 38 possessing sufficient weight to normally swing down to the position shown in Figure 2 and to compress the stack of bills 15. The follower may be of any appropriate construction being pivoted, as indicated at 76 39 to the side walls or other portions of the box and having a slotted forward edge 40, shown in Figure 4, to slide freely past the inwardly projecting end 30 of the register operating lever 26.

In the use of the device, the normal condition of the bank is shown in Figure 1, the appearance simulating that of an ordinary box. To insert a bill, the bill may be folded as shown in Figure 6. The bill is first folded upon a central transverse line 41 and then again folded upon the quarter transverse line 42, thereby producing a compact condition which avoids the necessity for great size in the construction of the bill bank.

The folded bill is flattened, and the hinged cover 35 raised to the dotted line position, shown in Figure 2. The raising of this cover will simultaneously expose the front slot 33 and raise the follower 38 as such follower is 90 coupled by the flexible string or other connection 43 to the lid. The string if desired can pass freely through an opening 44 made in the rear wall 9. The raised position of the follower is indicated in dotted lines in Figure 2. When the bill is introduced through the slot 33, it will be inserted beneath the follower.

Consequently when the cover 35 is subsequently returned to the closed position, the 100 follower will fall by gravity and force the bill downwardly and onto the false bottom 12 and stack 15. In so doing the bill will be forced past the shelves 32 which will yield for the purpose but promptly spring outward 105 to interfere with any bulging or swelling of the bills upwardly beyond this point which might permit their escape through the slot. Moreover, the bill in passing down will 110 strike the end 30 of the lever and depress this end slightly as permitted by the bottom of the slot 29. There results through the dog and ratchet mechanism 25 an angular movement in the register wheel 21. This angular movement will bring the next sub-division of the wheel opposite the opening 22 in the box and the amount of the movement will be the distance between the teeth 25.

As soon as the bill has passed the lever end, the spring 28 returns the released lever 115 to the upper position and places the pawl in condition for the next actuation.

The bill bank may be constructed of any size and possess any desired capacity. A compact bank for use in Christmas savings funds will hold fifty-one dollar bills and the register wheel 21 will be provided with fifty-one sub-divisions, the fifty-first and last sub-division being opposite the gap or slot 18 in the latch ring 17, so that as soon as the fifty- 120

first sub-division is presented at the opening 22, the gap 18 in the ring 17 will have arrived opposite the hook 16 on the main bottom 10. The hook will thus be released from the latch 5 ring and the bottom 10 may be either manually shifted down to the dotted line position shown in Figure 2, or it will be immediately and automatically projected to this position to disgorge the stack of bills 15 10 which by their accumulated pressure will be responsible for the automatic action referred to.

As the bills accumulate, the false bottom 12 will be forced downwardly in opposition 15 to the action of the spring 14 until the false bottom is very close throughout to the main bottom 10. The false bottom will, however, in the early stages and almost throughout 20 the entire stacking operation, hold the bills in an inclined position, so that the forward edges thereof are held lowermost and the bills are deposited with these forward lower edges downwardly against the stops 32 and the projecting end of the register lever to insure the 25 registering operation. The follower 38 is pivoted favorably to secure this same result and to co-operate with the inclination given the false bottom.

The opening 22 may be also used for the 30 purpose of inserting an instrument to pry loose a hook or fastening for the main bottom 10 when the bank is filled to capacity.

In Figure 7 is shown a preferred form of 35 bill follower 38, which is hinged at 39^a. Keyed to the pivot of this hinge device but at the exterior of the box is a rearwardly extending member 39^b, which is secured to the depending part of the cover 35, either at its rear or at the two lateral sides. Thereby a 40 positive connection between the operable cover 35 and the bill follower 38 is obtained. As the cover is opened, the follower 38 is raised to the dotted position, as shown in Figure 2, and as the cover descends or closes, 45 the follower 38 moves down to full line position shown in Figures 2 and 7. The false bottom is inclined so the entering end of the bills will rest on the false bottom at its most upper end, and the other or last entering edge 50 of the bill will rest on the yieldable and resilient steps 32. This, of course, takes place when the cover is open and the follower is out of the way, as when it is in the position of the dotted lines shown in Figure 2.

55 Then the cover is closed, and the follower 38 presses the rather stiffened edge of the folded bill downwardly, the yieldable steps 32 permitting this, and, at the same time, the edge of the bill presses upon and past the finger 30. The forked shaped end of the follower gives stiffness to the edge of the bill,

which enables this operation to be carried out. Once the bill pressed by the follower is forced past the finger 30, the bill is brought into a position where it cannot be taken out of the bank. The false bottom 12 is not essential, but I have found that the use of it has the advantage of placing the bills into position for the operation described. It is not essential to fold or crease the bills, as the bank can be made the full size of a bill, as now 70 made, or when smaller than now issued. The bank itself can be suitably decorated at its exterior and can be shaped like a treasure chest or in the shape of a book. The co-operation of the follower and finger rest gives 75 80 the edge of the bill a stiffness and rigidity so it can operate a counter.

It is obvious that various changes and modifications may be made in the details of construction and design of the above specifically 85 described embodiment of this invention without departing from the spirit thereof, such changes and modifications being restricted only by the scope of the following claims.

What is claimed is:

1. In a bank of the type having a container with a follower therein and a closure with a hook thereon; a ring mounted on the container for engagement with the hook of the closure and provided with a gap therein for 90 releasing the hook when the ring is turned to register the gap with the hook, a ratchet wheel connected to the ring for turning the same, and a lever pivoted to the container normally urged in one direction and having a pawl for engagement with said ratchet wheel, said lever having an inturned end lying in the path of said follower for engagement by the money moved by the follower to swing the lever and turn the ratchet wheel and ring 95 100 to release said hook.

2. In a bank of the type having a closed container for money and a hinged bottom on the container with a hook on the bottom, a locking ring mounted for rotation on the container and engaging the hook at times, and means operable on the ring and lying in the path of the money deposited in the bank and adapted to be actuated by the money to turn 105 said ring and release said hook.

3. In a bank of the type having a closed container for bills with a follower in said container for stacking the bills and a hinged closure for the container having a latch member; a cooperating latch element movably mounted on the container for holding the closure closed, and means operable by the bills engaged by the follower for actuating said latch element for releasing the closure.

In testimony whereof I affix my signature. 125
MARGARET GOEPEL.
